PUMPING APPARATUS FOR GREASE AND
THE LIKECharles W. Ginter, Bryan, Ohio, assignor to The
Aro Equipment Corporation, Bryan, Ohio, a
corporation of Ohio

Application July 10, 1937, Serial No. 152,959

8 Claims. (Cl. 221—47.1)

An object of my present invention is to provide comparatively simple apparatus for pumping heavy greases or the like, particularly from an original container such as a commercial grease drum.

In connection with heavy or sticky greases contained in shipping drums and the like, there has heretofore been a substantial problem involved in the transfer of such material to the reservoir of a pumping apparatus so that it could then be pumped by the apparatus to the bearings of a truck or bus.

It is therefore a further object of my invention to provide pumping apparatus in which a pumping unit floats on top of the grease or material to be pumped, while the material is still contained in the original container used for shipping it, both the weight of the unit and the vacuum created by its pumping operation serving to effect economically the discharge of grease at pressure from the container into a dispensing hose or the like.

Another object is to provide pumping mechanism wherein the travel of the material being pumped to the element of the pump which propels the material is reduced to a minimum, and such minimum is maintained throughout the entire material pumping operation performed in connection with a drum of grease, or the like.

Another object is to provide a pumping unit so designed that a follower plate for grease or the like being pumped thereby serves as a support for the pumping mechanism and also provides an effective seal against entrance of atmospheric air to the intake of the pump and eliminates the possibility of troublesome air pockets in the grease.

Still a further object is to provide pumping mechanism, which is especially adapted for pumping heavy greases and the like, such as are now commonly required in the bearings of trucks and buses, due to their heavy duty operation, the mechanism, however, being also applicable for pumping oils and light greases by a simple counterbalancing arrangement.

In connection with the structural features of the invention, one object is to provide a heavy duty valve mechanism for controlling the reciprocation of a compressed air operated power piston.

Another object is to provide in connection with such valve mechanism a means to prevent improper operation of the mechanism, due to a control stem extending from the power cylinder, and thereby subjected alternately to high and low air pressures.

Another object is to provide pumping mechanism for grease or the like which is double acting in character and which includes a combination piston and outlet valve.

Still another object of the invention is to provide a means whereby after the pumping mechanism has been operated to completely discharge the contents of a grease drum, the vacuum between the follower plate and the grease may be effectively broken, so that the pumping unit can be removed from the empty grease container and transferred to a full container for discharging its contents.

With these and other objects in view, my invention consists in the construction, arrangement and combination of the various parts of my pumping apparatus, whereby the objects contemplated are attained, as hereinafter more fully set forth, pointed out in my claims, and illustrated in the accompanying drawings, in which:

Figure 1 is a side elevation of my pumping apparatus for grease and the like, showing it mounted in a grease drum and counterbalanced for use in connection with light greases or oils.

Figure 2 is a vertical, sectional view of the same on an enlarged scale and omitting the counterbalance, the pumping mechanism in this figure being illustrated in connection with heavy grease, the grease pumping mechanism being shown started on the upstroke.

Figure 3 is an enlarged, sectional view of the lower end of the pumping unit, showing the mechanism adjacent the lower end of the downstroke.

Figure 4 is an enlarged, sectional view on the line 4—4 of Figure 2, the pump being turned a half revolution to simplify the description in connection with Figures 5, 6, 7 and 8.

Figure 5 is a sectional view on the line 5—5 of Figure 4, showing a rear elevation of the head of the pumping mechanism.

Figure 6 is a sectional view on the line 6—6 of Figure 4, showing an air-operated slide valve for the pumping mechanism together with an automatic control valve therefor.

Figure 7 is a sectional view on the line 7—7 of Figure 6, showing port connections for the automatic control valve.

Figure 8 is a sectional view on the line 8—8 of Figure 6, showing port connections for the air operated slide valve; and

Figure 9 is a sectional view on the line 9—9 of Figure 4, showing port connections between the slide valve and opposite ends of the power cylinder, and illustrating a mechanism to insure

proper operation of the automatic control valve.

On the accompanying drawings, I have used the reference character C to indicate an original container such as a commercial grease drum for 5 grease or other fluid material to be pumped by my pumping apparatus. Within the container C, the grease is indicated at 10.

My pumping mechanism includes a follower plate 11 on which is mounted a grease pump G 10 and a power device P for operating the grease pump.

The grease pump G includes a cylinder 12 within which is reciprocably mounted a combination piston and outlet valve 13 (see Figure 3). The 15 piston and valve 13 is sleeve-like in character and a lapped fit relative to the cylinder 12. The piston and valve sleeve 13 has a bore 14. Through the bore 14 a piston rod 15 extends. The portion of the rod within the sleeve 13 is 20 enough smaller in diameter than the bore 14 to provide a space 16 for the passage of grease.

On the lower end of the cylinder 12 is a sleeve 17, which extends through the follower plate 11 and is sealed relative thereto. The seal may consist of a gasket washer 18 enclosed in a circular flange member 19.

Within the sleeve 17, I provide a liner 20 having a foot valve seat 21. A foot valve 22 normally seats thereon. The valve 22 has a stem 23 30 slidably mounted in a hub 24. The hub 24 is part of a spider which has an annular rim 25. The rim 25 is confined between a shoulder 26 of the liner 20 and a spacer sleeve 27. A gasket is provided at 27a.

35 Above the piston 13 and extending through the piston rod 15, I provide a stop pin 28. The pin 28 may be retained in position by a retainer wire 29. The pin 28 is spaced far enough from a head 30 on the lower end of the piston rod 15 to permit 40 limited movement of the piston 13 relative to the piston rod 15 as will hereinafter be described in connection with the operation of the device.

The power mechanism P for operating the pumping mechanism thus far described includes 45 a piston, the construction of which is best shown in Figure 9.

The piston rod 15 at its upper end has an annular groove 31 in which is mounted a split ring 32. The ring 32 is confined between a pair of 50 plates 33 secured together by cap screws 34.

The peripheries of the plates are shouldered to receive cup leathers 35, which cooperate with the wall of a cylinder 36. The cup leathers 35 are normally expanded against the wall of the 55 cylinder by coil springs 37.

The cylinder 36 has a base head 38 and an upper head 39. The heads 38 and 39 are assembled relative to the ends of the cylinder 36 by tie rods 38a. Gaskets 39a are interposed between the 60 ends of the cylinder 36 and the heads 38 and 39.

The base head 38 is connected to the upper end of the grease cylinder 12. The means of connection is illustrated as comprising an annular groove 40 in the cylinder 12 adjacent its upper 65 end, a split ring 41 positioned therein, and a retainer plate 42 for the ring. The retainer plate 42 as shown in Figure 2 is secured in position by cap screws 43.

Within the base head 38, packing washers 44 70 are provided to minimize the leakage of air downwardly from the cylinder 36 past the piston rod 15. The packing washers 44 are retained in position by a ring 45 which engages the upper end of the grease cylinder 12.

75 An expansion ring 45a is provided for the pack-

ing washers 44. A spring 46 is provided for the expansion ring 45a. The upper end of the spring 46 seats against a washer 47 which is retained in position by a wire ring 48.

To eliminate any possibility of air entering the 5 grease being pumped or grease entering the air chamber in the lower end of the cylinder 36, a 10 vent is provided between the packing 44 and the piston rod 15 and its cylinder 12 at a lap fit portion 12a thereof. This is shown as an annular 15 groove 44a, a radial groove 46a and a vent hole 47a (see Figure 9).

A slide valve mechanism is provided for alternately admitting air to opposite ends of the power cylinder 36 and at the same time exhausting 15 air from the opposite end. The slide valve mechanism comprises (see Figures 6 and 8) a valve block 49 slidable against a valve plate 50. The plate 50 has an exhaust port 51 discharging to atmosphere and ports 52 and 53 communicating 20 respectively with the upper and lower ends of the cylinder 36.

The means of communication between the port 52 and the upper end of the cylinder 36 comprises a passageway 54 (see Figure 9). The means of 25 communication between the port 53 and the lower end of the cylinder 36 comprises passageways 55 and 56. The passageways 55 and 56 are connected together by a pipe 57 sealed relative to the passageways 55 and 56 by gasket washers 58 and 30 59. A nut 60 screwed onto the lower end of the pipe 57 is provided for tightening the gasket washers.

The valve block 49 is reciprocated relative to the valve plate 50 by a stem 61. The stem 61 has 35 a pair of flanges 62 for engaging the opposite ends of the valve block 49 for this purpose. One end of the stem 61 has a head 63 slidable in a bore 64 of a valve body 65. The valve body 65 is mounted on the upper cylinder head 39 by cap 40 screws 66.

The other end of the valve stem 61 is provided with cup leather pistons 67 and 68. These reciprocate in cylindrical bores 69 and 70 respectively. A vent 69a is provided to compensate for 45 changes in volume in the cylinders 69 and 70 between the pistons 67 and 68. The bore 70 is closed by a plug 71.

The valve block 49 is mounted in a chamber 12 of the valve body 65, which is in communication with an air nipple 73. A source of compressed air is connected with the nipple 73 as 50 by an air hose 74, as shown in Figure 1.

Within the chamber 12, I provide an automatic control valve, including an oscillating valve 55 block 75. The block 75 oscillates on the face of the valve plate 50, which plate is provided with a port 76. The port 76 communicates by passageways 77 and 78 with the cylindrical bore 70 (see Figures 6 and 7).

The valve block 75 is provided with a port 79 on the surface thereof next to the plate 50, the port 79 being milled into the block 75. One end of this port is adapted at times to communicate with the port 76 while the other end is adapted 65 to communicate through ports 80 with an exhaust bore 82 of a tubular oscillating shaft 83. The shaft 83 has the valve block 75 keyed to its inner end and an operating arm 84 keyed to its outer end. 70

The operating arm 84 has a fork portion co-operating with a flanged spool-like sleeve 85 (see Figure 9). The sleeve 85 is adjustably mounted on a stem 86. The stem 86 extends through a packing gland 87 into the cylinder 36. 75

The lower end of the stem 86 has a head 88. The head 88 is reciprocable relative to a bore 89 in the upper end of the piston rod 15. The bore 89 is enlarged sufficiently to prevent any binding of the parts and permits escape of air from the bore around the head 88. A stop plate 90 is provided for the head 88. The plate 90 is retained by screws 91 on the upper surface of the upper piston plate 33.

10 In conjunction with the automatic valve including the oscillating valve block 75, I provide a plunger 92 (see Figure 9) mounted in a cylindrical bore 93. It is packed relative thereto by a flanged type packing 94. The bore 93 communicates by a passageway 95 with the passageway 55.

15 On the follower plate 11, I provide a valve fitting 96 having a check valve 97 normally spring-closed. The valve fitting 96 communicates by means of a tube 98 with an air nipple 99 (see Figure 5). The air nipple 99 is mounted in a boss 100 with which the upper end of the tube 98 is connected. The boss merely serves as a support for the nipple 99 and has a means for connecting it with the tube 98. The tube 98 has a fitting 101 screwed into the boss.

20 The nipple 99 is normally covered by a dust cap 102. This cap is readily removable so that an air or tire chuck can be applied to the nipple 99 for releasing the vacuum under the follower plate 11 as will hereinafter be described.

25 When my pumping apparatus is used for pumping relatively heavy or stiff grease, it will operate properly by merely resting it with its follower plate 11 on the upper surface of the grease 10 as shown in Figure 2. When it is to be used with light greases and oils, however, it is necessary to counterbalance it to a certain degree, depending on the viscosity of the lubricant or other material being pumped.

30 40 In Figure 1, I illustrate a counterweight 103 for this purpose, connected by a cable 104 to a supporting eye 105 of the pumping mechanism. The cable 104 extends over pulleys 106. The eye 105 is mounted in the head of a casing 107 for the power mechanism P. The lower end of the casing 107 is enlarged as at 108 and has its lower end connected with the periphery of the follower plate 11. The diameter of the casing 108 is preferably slightly less than the internal 45 diameter of the container C so that it substantially wipes the wall thereof during the settling of the pumping apparatus in the container C as the apparatus is operated.

50 55 A discharge pipe 109 is provided for the grease pump G which communicates by a fitting 110 with the side of the grease cylinder 12. The fitting 110 includes an outlet check valve 111. The upper end of the pipe 109 extends from the upper end of the casing 107 and is connected by a hose 60 112 to a discharge nozzle or valve 133.

Practical operation

65 In the operation of my pumping apparatus, the power piston in Figure 9 and the grease piston in Figure 3 have just reached their lower limit of movement. During the downstroke, the foot valve 22 is retained closed by the pressure of grease in the cylinder 12 and the grease passes up through the bore 14 of the piston sleeve 13. The 70 grease is thus confined in the cylinder 12 by the foot valve 22 and during the downstroke is displaced therefrom through the outlet check valve 111, fitting 110, pipe 109 and hose 112 to the control valve 113.

On the upstroke as shown in Figure 2, the head 30 of the piston rod 15 engages the lower end of the piston sleeve 13, thus acting as an outlet valve. The sleeve 13 displaces the grease above it through the pipe 109 as the upstroke proceeds and thus by having the piston rod 15 relatively large, there is substantially equal displacement both upon the up and down strokes of the pumping mechanism, thereby providing a double acting pump.

10 During the upstroke, the valve 22 opens due to the vacuum created within the liner sleeve 20 and the grease 10 is drawn in past the valve. The grease taken in is that adjacent the valve 22 and there is a general movement of the grease from the periphery of the follower plate 11 toward the foot valve 22 during the upstroke. This causes a slight settling of the entire unit during each upstroke, while the relatively large surface of contact between the grease and the follower plate and also between the periphery of the cylindrical casing 108 and the interior wall of the grease container C provide an effective seal against atmospheric air entering the pump. The weight of the pumping unit also serves to eliminate any air pockets in the grease while the proximity of the grease pump G to the lower surface of the follower plate reduces the necessity of drawing the grease any distance to a minimum. This obviously is particularly desirable 25 in connection with heavy greases and by having the pumping unit following the receding surface of the grease, this minimum distance is maintained.

30 35 The downstroke of the power piston in Figure 9 has rocked the control lever 84 in a clockwise direction, thus rocking the valve block 75 of Figure 6 in a counter-clockwise direction (shown by full lines). This connects the port 76 with atmosphere through the exhaust bore 82 of the 40 tubular oscillating shaft 83 to discharge compressed air from the valve cylinder 70 of Figure 8. The chamber 72, it will be remembered, is constantly charged with compressed air from the nipple 73. Accordingly when the air is discharged to atmosphere from the cylinder 70, the air in the chamber 72 acts upon the piston 67 to change the position of the slide valve 49.

45 Such change in position of the slide valve will connect the port 52 with the exhaust port 51, 50 thus permitting escape of air through the passageway 54 from the upper end of the power cylinder 36. At the same time, the port 53 of Figure 8 will be uncovered, so that compressed air from the chamber 72 will pass through the passageways 55 and 56 and through the pipe 57 to the bottom of the power cylinder 36. This will cause the desired upward movement of the pumping mechanism.

55 60 Such upward movement does not begin however until sufficient air has been exhausted from the upper end of the cylinder 36 and sufficient compressed air has been admitted to the lower end thereof to overcome the pumping load, and friction between the working parts. For instance, 65 the incoming air may be at 100 lbs. per square inch while the exhausting air may be at 40 lbs. per square inch when the upward movement starts. Due to the loose fit around the head 88 of the stem 86, the pressure in the bore 89 equalizes relative to any pressure in the upper end of the cylinder 36.

70 75 Obviously any pressure in the upper end of the cylinder sufficiently in excess of atmospheric pressure to overcome the friction of the pack-

ing 87 and of the arm 84, etc. operated by the stem 86, will tend to expell the stem from the cylinder. As soon as the piston 35 moves upwardly there is accordingly a tendency for the stem to simultaneously move upwardly with the plate 90 and soon reverse the position of the control valve 75. This would result in undesired short reciprocations of the piston 35 adjacent the bottom of the cylinder 36.

10. The plunger 92 is provided to overcome such undesirable operation of the valve mechanism. Whenever the passageway 55 is charged with compressed air for causing the upstroke of the piston 35, the cylinder 93 for the plunger 92 is also charged. This is possible by the communicating passageway 95 between the passageway 55 and the cylindrical bore 93. The air pressure on the plunger 92 (which is larger in diameter than the stem 86) positively guards against any 20 undesired movement of the stem 86 upwardly except when the lower end of the bore 89 in the piston rod 15 engages the head 88 to raise the stem.

At the completion of the upstroke of the power 25 piston, the head 88 is engaged by the lower end of the bore 89 of the piston rod 15 to reverse the position of the valve block 75 from its full line position in Figure 6 to its dotted position. This uncovers the port 76 so that compressed air 30 from the compartment 72 enters it and flows by way of the passageways 77 and 78 to the cylinder

10. In the cylinder 70, the air acts upon the piston 68 to force the valve block 49 to the position shown in Figure 8. This movement occurs 35 because the piston 68 is larger in diameter than the piston 67 and the same air pressure on each therefor permits an unbalancing of forces, causing the stem 61 to travel toward its righthand limit of movement.

40. When the valve block 49 assumes the position shown in Figure 8, the port 52 is uncovered so that compressed air from the compartment 72 will enter it while the air from the port 53 will be discharged through the port 51 to atmosphere. 45 This exhausts the air from the lower side of the power piston and from the plunger 92 and permits air to enter the cylinder 36 above the piston 35 therein to thus cause downward reciprocation of the power piston. At the lower end of the stroke, 50 the cycle of operations thus far described will be repeated.

After the contents of the container C have been 55 discharged through the hose 112 and it is desirable to transfer the pumping unit to another filled drum of grease, it would be extremely difficult to lift the pumping unit out of the container C because of the vacuum connection between the grease in the container and the follower plate 11. This vacuum is readily released, however, by 60 removing the dust cap 102 (see Figure 5) and applying a tire or compressed air chuck to the nipple 89. This will cause compressed air to flow through the valve 97 to provide an air pocket under the follower plate 11, and thus release the 65 vacuum tending to retain the plate in engagement with the grease. The periphery of the plate 11 has a down-turned flange 11a to aid in this operation by confining the compressed air under the plate and above the surface of the grease until 70 the vacuum has been released. Thereupon the air will start bubbling up through the grease film between the casing 108 and the container C to notify the operator that the vacuum releasing operation is completed.

75. By mounting the pumping unit directly on the

follower plate and permitting it to be entirely supported thereby, I provide a very efficient means for minimizing the distance between the intake of the pump and the grease ahead of the follower plate. This also provides an efficient sealing means to guard against air entering the pump.

Some changes may be made in the arrangement and construction of the various parts of my pumping apparatus, without departing from the 10 real spirit and purpose of my invention, and it is my intention to cover by my claims, any modified forms of structure or use of mechanical equivalents, which may be reasonably included within their scope. 15

I claim as my invention:

1. In a pumping apparatus for grease and the like, a follower plate for grease in a container, a drumlike extension upwardly from the periphery of said follower plate, said follower plate and extension being freely movable in said container and said extension constituting a guide for said follower plate to prevent canting thereof in said container, and pumping mechanism mounted on said follower plate and carried thereby so as to 25 keep said follower plate in contact with the grease solely by the weight of said drumlike extension and the suction created by said pumping mechanism, said pumping mechanism having an intake at the surface of said follower plate which 30 is in contact with the grease.

2. In a pumping apparatus for pumping grease and the like from a container, a follower plate loosely fitting the inner wall of the container and pumping mechanism mounted thereon, carried thereby, and having an intake pipe provided with an intake opening at the surface thereof which is in contact with the grease, said pumping mechanism including a grease propelling means located closely adjacent said intake opening and an intake valve mounted in the extreme lower end of said intake pipe. 40

3. In a pumping apparatus for use with a container of fluid material, pumping mechanism having an intake and an outlet, and means for 45 mounting said pumping mechanism relative to a container of fluid material comprising a base plate for positioning on the surface of the fluid material, a tubular wall extending upwardly from the periphery of said base plate, said base plate 50 and tubular wall being guided by the inner wall of the container and both being of smaller diameter than said inner wall to permit free settling of the base plate and tubular wall under the influence of the weight of said mechanism without canting the base plate and tubular wall with respect to the container, said intake of said pumping mechanism being located on the under surface of said base plate, said under surface contacting with said fluid material throughout 60 substantially the entire area of said under surface to prevent atmospheric air from passing downwardly between said inner wall and tubular wall, flowing across said under surface and entering said intake. 65

4. In a pumping apparatus for use with a container of fluid material, pumping mechanism having an intake and an outlet, and means for mounting said pumping mechanism relative to a container of fluid material, comprising a base 70 plate for positioning on the surface of the fluid material, said intake being located on the under surface of said base plate, and a counterweight for counterbalancing said base plate and pumping mechanism to prevent excessive settling 75

thereof relative to the surface of said fluid material.

5. In a pumping apparatus for fluid material, a follower plate for fluid material within a container, said plate substantially filling the interior of the container, and pumping mechanism mounted on said follower plate, carried thereby and having an intake communicating with the surface thereof which is in contact with the fluid material, said pumping mechanism including a cylinder, a piston therein and a piston rod extending from said cylinder, said piston rod having a cross sectional area substantially half as large as the cross sectional area of said cylinder 10 to cause substantially equal displacement of material from said cylinder when said piston is moving in either direction relative thereto.

6. In a pumping apparatus for fluid material, a follower plate for such material, pumping mechanism mounted on said follower plate, carried thereby and having an intake at the surface thereof which is in contact with the fluid material, an air conduit communicating with said surface for discharging air thereto to positively 20 release said plate from contact with the fluid material, said conduit extending upwardly from

said follower plate and terminating in an intake end adapted to receive compressed air to effect such positive release.

7. Pumping apparatus for pumping material from a container comprising a pump, fluid pressure means for operating said pump, and a support for said pump, said support comprising a follower plate for the material being pumped, said follower plate being freely movable in said container under the influence of the weight of 5 said fluid pressure means and pump.

8. In a pumping apparatus for grease and the like, a follower plate for grease in a container, a tubular extension upwardly from the periphery of said follower plate, said follower plate and 15 tubular extension being freely movable in said container with said tubular extension adjacent the inner wall of the container to guide the apparatus relative to the container and to prevent canting of said follower plate therein and pumping mechanism mounted on said follower plate and carried thereby and having an intake at the surface thereof which is in contact with the grease.

CHARLES W. GINTER. 25
